UNITED STATES PATENT OFFICE.

ELAM E. ROOT, OF LANCASTER, PENNSYLVANIA, ASSIGNOR TO JOHN F. HAAS, OF LANCASTER, PENNSYLVANIA.

VEHICLE-WHEEL SPINDLE.

SPECIFICATION forming part of Letters Patent No. 705,968, dated July 29, 1902.

Application filed October 2, 1901. Serial No. 77,269. (No model.)

To all whom it may concern:

Be it known that I, ELAM E. ROOT, a citizen of the United States, residing at Lancaster, in the county of Lancaster and State of Pennsylvania, have invented certain new and useful Improvements in Vehicle-Wheel Spindles and Bearing-Boxes; and I do hereby declare the following to be a full, clear, and exact description of the invention, such as will enable others skilled in the art to which it appertains to make and use the same.

This invention relates to improvements in a vehicle-wheel spindle and bearing-box of that class in which the box is secured in axial position to the hub between the front and rear end points of impact and in which the box is revolubly secured to the spindle by a divided ring or adjusting screw in its rear end and against a shoulder of the spindle, said divided screw being locked in place by a ring screw thereon and against the rear end of the box.

The object of the invention is the production of a vehicle-wheel spindle and box simple in construction, effective in use, readily applied, and adjustable to take up lost motion without washers, being antirattling, self-oiling, and dust-proof, yet holding the wheel in position without the usual forward end spindle-nut.

The elements of the invention will severally and at large appear in the following description, and they will be severally or combinedly pointed out or set forth in the appended claims.

The purposes of the invention are attained by the mechanism, devices, and means illustrated in the accompanying drawings, similar reference characters designating like parts throughout the several views, in which—

Figure 1 is a longitudinal vertical central section of a vehicle-wheel hub, showing the elements of the invention in position, the spindle appearing in full side elevation. Figs. 2 and 3 are completed end views of Fig. 1 with the rear end dust-shield omitted in Fig. 3. Figs. 4 and 5 are respectively an inverted plan and a full side elevation of the box-secur ing nut detached from Fig. 1. Figs. 6 and 7 are completed and detached end elevations of the box. Figs. 8 and 9 are full end elevations, detached, of the spindle. Figs. 10 and 11 are completed and detached side and end

elevations of the divided adjusting-screw, and Figs. 12 and 13 are similar elevations of a lock or jam screw.

In the axis of a hub 1, supporting spokes 2 and having rear and front end hub-bands, (designated, respectively, by 3 and 4,) is seated a bearing-box A, having a rearwardly-widening portion a , with an outwardly-sloping conical portion a' and a rear end cylindrical portion a'' , said latter portion having interiorly a screw-thread a^3 extending a prescribed distance forward from its rear end and exteriorly a prescribed thickened portion a^4 , with longitudinal ribs a^5 extending to the slope of the conical portion, which is thickened, as shown, while the forward end of the box beyond the hub end has an external screw-thread a^6 , onto which is firmly screwed home a nut A', having a flanged ring base a^7 to engage against the forward end of the hub, and the nut is interiorly hollowed out, forming an oil-storing chamber a^8 , with a central opening a^9 through its head-wall admitting the oil. The rear end thickened portion a^4 , with the forward surface of the conical portion a' and the contact-surface of the screw-base a^7 , constitute the points of impact between which said hub and box are bound firmly together, the ribs a^5 holding them revolubly in place.

Seated in the box A is an axle-spindle B, with its portion b fitting the box portion a , its conical portion b' the box portion a' , its prescribed cylindrical portion b^2 the box portion a^3 to a prescribed extent, where is formed an abrupt shoulder b^3 , and the spindle diametrically reduced, forming a prescribed cylindrical portion b^4 , having a diameter equal to the diagonal extent of the square axle portion b^5 , adapted to be welded to an axle-body well known to the trade in the construction of vehicles using such spindles, while in the top of the portion b is an oiling-groove b^6 , extending to the base of the conical portion b' ; but this groove may be extended up the slope of said conical portion and over the cylindrical portion b^2 to the abrupt shoulder b^3 , as indicated by dotted lines b^7 .

On the portion b^4 is sleeved a ring screw C, with an external screw-thread c engaging the thread a^8 of the box and being screwed home therein and against the shoulder b^3 serves to secure the spindle and box together as well as to take up the lost motion that may occur.

between the contact-surfaces of the spindle and box and to adjust the contact-surfaces between their conical portions. In order that said screw may be placed in position on said portion b^4 , it is diametrically divided by longitudinal cuts c' into sections $c^2 c^3$, the section c^2 having transverse notches c^4 in said cuts and the section c^3 projections c^5 to engage in said notches, holding said sections together and the thread c continuous, while in the rearward edges of the sections are orifices c^6 , to be engaged by the points of a pin-wrench (not shown) in turning or rotating said screw.

15 To lock or securely hold the screw C in place after being screwed home in adjusting, a ring screw D , having a screw-thread d in its inner face and orifices $d' d'$ in its rearward end edge, is screwed home on said screw C , with its forward end edge d^2 seated firmly against the rearward end edge of the box, with the thread d engaging on the thread c and the orifices d' serving to be engaged by the points of a pin-wrench in turning said screw D home.

25 A washer or collar E may be applied to the rear end of the hub, as shown, and secured thereto in any approved manner, which washer, together with the nut A' , making the joint between the spindle, box, and hub to be practically dust-proof.

Now the several parts hereinbefore described and occupying the respective positions indicated in the drawings, the following observations will be noted: first, that by reason of the body of the hub being between the points of impact of the portion a^4 with the conical slope a' and the flange-surface a^7 of the nut A' the hub and box are lengthwise rigidly secured; second, that by reason of the ribs a^5 engaging in the body of the hub the two are revolubly secured together; third, that the convex surface b' contacting with the concave surface a' and the forward end edge of the screw C engaging against the shoulder b^3 securely holds the wheel to the spindle without the usual axle-nut; fourth, that the screw C with its forward end edge engaging against the shoulder b^8 serves to adjust the spindle in the box, taking up lost motion endwise thereof without washering; fifth, that the screw C , being divided by the cuts c' , may be placed in position on the portion b^4 after joining the spindle to the axle-body; sixth, that the lugs c^5 , engaging in the notches c^4 , serve to hold the sections $c^2 c^3$ securely in place, preserving the continuity of the thread c ; seventh, that the screw D on the screw C being firmly screwed home against the rear end of the box securely locks said screw C in place; eighth, that the chamber a^8 within the nut A' serves to carry a supply of oil for automatic or self lubrication; ninth, that the orifice a^9 serves to admit oil, and, tenth, that the groove b^6 aids in said lubrication.

The invention having been thus ascertained and described and the manner in which it is

performed fully shown and set forth, what is considered new, and desired to be secured by Letters Patent, is—

70

1. The combination in a vehicle-wheel spindle and bearing, with the box, A , having the rearwardly - widening portion, a , the outwardly-sloping conical portion, a' , with the thickened wall, and the rearwardly-extending cylindrical portion, a^2 , having the internal screw-thread, a^3 , with means provided for securing it axially to a wheel-hub, of the spindle, B , seated in said box, said spindle having the rearwardly-widening portion, b , the outwardly - sloping conical portion, b' , the rearwardly-extending cylindrical portion, b^2 , having the abrupt shoulder, b^3 , and the cylindrical portion, b^4 , having the angular rear end portion, b^5 , with means provided, such as a divided screw, to revolubly hold said spindle in place, substantially as and for the purpose hereinbefore set forth.

75

2. The combination in a vehicle-wheel spindle and bearing, with the box, A , as described, axially secured to a wheel-hub as shown, and the spindle, B , as described, seated in said box as shown, said box having the internal screw-thread, a^3 , and said spindle having the abrupt shoulder, b^3 , with the cylindrical portion, b^4 , of the divided screw, C , with the external screw-thread, c , sleeved on said portion, b^4 , screwed into said box and against said shoulder, b^3 , substantially as described and for the purpose hereinbefore set forth.

80

3. In a vehicle spindle and bearing with the box, A , as described, axially secured to a wheel-hub as shown, and the spindle, B , as described, seated in the box as shown; said box having the internal screw-thread, a^3 , and said spindle the abrupt shoulder, b^3 , with the cylindrical portion, b^4 ; the divided screw, C , with the external screw-thread, c , sleeved on said portion, b^4 , screwed into said box and against said shoulder, b^3 ; said screw, C , having the diametrical longitudinal cuts, c' , making the sections, $c^2 c^3$, with the notches, c^4 , and the projections, c^5 , engaging said notches, and with means provided to lock said screw, C , in place; all substantially as described and for the purpose hereinbefore set forth.

85

4. In a vehicle-wheel spindle and bearing, with a hub, 1 , having the box, A , as described, axially secured into said hub, the spindle, B , as described journaled in said box, and the screw, C , as described screwed thereinto and against the shoulder, b^3 ; the ring screw, D , with the internal screw-thread, d , screwed onto said screw, C , and against the rear end of said box, substantially as described and for the purpose hereinbefore set forth.

90

In testimony whereof I affix my signature in presence of two witnesses.
